United States Patent Office

Des. 218,794
Patented Sept. 29, 1970

218,794

SKI BOOT

Willy Kaufmann, Kreuzlingen, Switzerland, assignor to Raichle Boot Company, Ltd., Kreuzlingen, Switzerland

Filed Sept. 4, 1968, Ser. No. 13,398

Term of patent 14 years

Int. Cl. D2—04

U.S. Cl. D2—276

FIG. 1

FIG. 2

FIG. 3

FIG. 4

FIG. 5

FIG. 6

FIG. 1 is a side elevational view of a ski boot embodying my new design;

FIG. 2 is a side elevational view of the side opposite to that shown in FIG. 1;

FIG. 3 is a front elevational view thereof;

FIG. 4 is a rear elevational view;

FIG. 5 is a top plan view; and

FIG. 6 is a bottom plan view.

I claim:

The ornamental design for a ski boot, substantially as shown.
